Primary Examiner — Lakiya Rogers*Assistant Examiner* — Carissa C Fitts(74) *Attorney, Agent, or Firm* — Brinks Gilson & Lione(57) **CLAIM**

We claim the ornamental design for a cell collection device, as shown and described.

DESCRIPTION

FIG. 1 is a front and top perspective view of a cell collection device of the present invention;

FIG. 2 is a top view thereof, the bottom view being a mirror image thereof;

FIG. 3 is a front view thereof;

FIG. 4 is a first side view thereof, the second side view being a mirror image thereof;

FIG. 5 is a rear view thereof;

FIG. 6 is an enlarged front and top perspective view of the forward portion thereof;

FIG. 7 is an enlarged top view of the forward portion thereof;

FIG. 8 is an enlarged front view thereof; and,

FIG. 9 is an enlarged rear view thereof.

The broken lines shown represent unclaimed subject matter and form no part of the claimed design.
